Primary Examiner — Marianne Pandozzi*Assistant Examiner* — Jae Liang(57) **CLAIM**

The ornamental design for a bottle, as shown and described.

DESCRIPTION

FIG. 1 is a front, first side, top perspective view of a bottle in a closed configuration showing my new design; FIG. 2 is a rear, second side, bottom perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a front, first side, top perspective view of a bottle in an open configuration; and,

FIG. 10 is a front, second side, bottom perspective view of a bottle in an open configuration.

The broken lines in the drawings depict portions of the bottle that form no part of the claimed design.

The trademark material "Radix" forms part of the claimed design. The owner of the registered trademark is Arthur Wu, DBA Radix Products LLC located at 5040 Tujunga Ave Suite 17 North Hollywood, Calif. 91601.

1 Claim, 9 Drawing Sheets(56)
